US00D858558S

(12) **United States Design Patent**
Sabatelli et al.

(10) Patent No.: **US D858,558 S**
(45) Date of Patent: ** Sep. 3, 2019

(54) **DISPLAY SCREEN OR PORTION THEREOF
WITH GRAPHICAL USER INTERFACE**

- (71) Applicant: **Apple Inc.**, Cupertino, CA (US)
(72) Inventors: **Alessandro Francesco Sabatelli**, San Francisco, CA (US); **Brian Andrew Schmitt**, San Francisco, CA (US)
(73) Assignee: **Apple Inc.**, Cupertino, CA (US)
(**) Term: **15 Years**
(21) Appl. No.: **29/673,674**
(22) Filed: **Dec. 17, 2018**

CLAIM

The ornamental design for a display screen or portion thereof with graphical user interface, as shown and described.

DESCRIPTION

FIG. 1 is a front view of a display screen or portion thereof with graphical user interface showing the claimed design; FIG. 2 is a second embodiment thereof; FIG. 3 is a third embodiment thereof; and, FIG. 4 is a fourth embodiment thereof.

The broken lines in the figures show a display screen or portion thereof, and form no part of the claimed design.
